UNITED STATES PATENT OFFICE.

PETER BULGER, OF SHANER STATION, PENNSYLVANIA.

WASHING-MACHINE.

SPECIFICATION forming part of Letters Patent No. 352,443, dated November 9, 1886.

Application filed February 26, 1886. Serial No. 193,337. (No model.)

To all whom it may concern:

Be it known that I, PETER BULGER, a citizen of the United States, residing at Shaner Station, (Yohoghany P. O.) in the county of 5 Westmoreland and State of Pennsylvania, have invented certain new and useful Improvements in Washing-Machines; and I do declare the following to be a full, clear, and exact description of the invention, such as will enable 10 others skilled in the art to which it appertains to make and use the same, reference being had to the accompanying drawings, and to the letters and figures of reference marked thereon, which form a part of this specification.

15 My invention relates to that class of washing-machines known as "roller and bed;" and has for its object to provide a machine which will cleanse equally well light or heavy large or small articles of personal wear or domestic use in a thorough manner, and which will be of few parts, not liable to get out of repair, and easy to operate; and it consists of the parts and combinations of parts hereinafter described and claimed.

25 In the accompanying drawings, forming a part of this specification, Figure 1 is an end elevation of my improved machine; Fig. 2, a cross-section; Fig. 3, a plan view; Fig. 4, a perspective view of the concave; Fig. 5, a detail view of the auxiliary spring, and Fig. 6 a detail view showing the arrangement of the splash-plates.

Similar letters refer to similar parts throughout the several views.

35 A represents a suds box or tub, being in this instance shaped so as to flare outwardly on both sides, the ends being vertical; but it may be of any other suitable shape. Openings B are formed in the upper edges of the ends of 40 the box, and around these openings on the inner sides of the ends square pieces of galvanized iron or zinc a are inserted and secured, (see dotted lines in Fig. 1 and detail view, Fig. 6,) so that a space is left between them and the inner surface of the ends of the box to receive the splash-plates r, each of the latter being provided with an opening in its center through which the axle h² of the roller or drum H passes. These plates r prevent the suds 45 slopping out through the openings B when the

machine is in operation. As an additional defense against splashing of the suds, I provide the galvanized iron or zinc fenders s, which are attached to the removable side pieces, T, and also project down into the space between the pieces a and the inner surfaces of the ends of the box. These fenders s extend beyond the pieces a some distance on each side of the concave M, as clearly shown in Fig. 2. On 55 one side of and within the box I secure upright guides C, and to the bottom of the box, immediately at the lower ends of the guides, are secured the retaining-irons b. These irons extend across from side to side of the box and have their ends bent, the ends nearest the 60 guides being turned completely over and the opposite ends being bent at right angles. On these irons the curved flat springs P, which are attached to and form a yielding support for the concave or bed M, rest, the bent ends 65 of the irons forming stops for the ends of the spring P.

The concave or bed M is formed of slats or staves o, which, as shown in Fig. 2, when in their normal position only touch each other at 70 their inner edges, a triangular space separating their bodies, owing to the fact that their edges are beveled. The staves o are secured in any suitable manner to the spring-metal bands O, to form a concave, and are provided with the 75 galvanized iron or zinc rubbing-surface n, corrugated in the usual manner. This rubbing-surface is secured to the concave at its ends only, leaving it wholly free of the body of the concave from end to end, whereby the concave 80 can more readily adjust itself to any inequalities of the material under treatment. To the bands O on the side of concave next to the guides, which is the longest side of the concave, I attach the flat springs O', the lower 85 ends of which are bent or slightly rounded, so that they will move easily in the guides C without creating too great friction.

To the ends of the box, on the inside, a short distance above the bottom, plates d are secured 90 by screws or otherwise, into which the bent ends of the rock-shaft or rod D are journaled. To this shaft a rod, E, is secured, by which the said shaft may be operated. The shaft D is forced down upon the springs P to hold the 95

same securely in position, the upper end of rod E being bent so as to fit into a recess or catch, e, formed in the side of the box to hold the shaft down. When it is desired for any reason to remove the concave, the rod E is released from the recess e, permitting the springs P to force the shaft D and rod E upwardly, when the concave can be readily lifted from the box.

On the axle h² the drum or roller H is hung. 10 This drum is constructed in the usual way, with a corrugated metal surface tenoned in disks which project slightly beyond the corrugated surface. The axle h² is journaled in bearings h, Fig. 3, which are welded or riveted to the 15 springs F, one on each of the boxes. These springs are somewhat elliptical in shape, or curve upwardly in both directions from their centers and then downwardly to their ends, where they terminate in eyes. One end of 20 each spring F is hinged by means of its eye g' and a removable pin to the upper end of a short stiff spring, G, the lower end of which is secured to the flange of the box. The pins are retained in place by flat springs g², which 25 are secured to the edges of the flanges of the box and project over the heads of the pins and prevent them working out. The opposite ends of the springs F are supported by the bent ends k of a lever or rod, K, which is ful- 30 crumed or journaled in the ends of supporting-irons L, attached to the flanges of the box. The bent ends k of the lever K enter the eyes on the ends of the springs F. To adjust and support the lever K, I attach a short rod, m, 35 to the end of bent arm of the lever K, outside of eyes on springs F, the lower end of which is adapted to be inserted in the openings l of irons L. Thus it will be seen that by simply moving the rod m up or down greater or less 40 pressure is brought to bear, through the medium of the springs F, on the drum or roller H, and through that on the articles being cleansed, and that the concave, being flexible, will adjust itself so as to accommodate 45 articles of different size and varying quantities to be washed.

As will be observed from the foregoing description, the drum is self-adjusting; or, in other words, it being hung or supported on 50 springs will always return to the position to which it has been adjusted by the rod m. The openings B are sufficiently large to permit great latitude to the axle, which is capable of moving in all directions, owing to the peculiar 55 shape of springs F. The plates r follow the axle in all movements, the piece a, being much larger than the plate, permitting of this. Cranks W are attached to the axle, by which the machine is operated.

60 The above description embraces an operative machine; but to further brace the concave, when very large articles are to be washed, I provide the auxiliary spring device shown in detail in Fig. 5. This consists of the plate p, secured to one side of the 65 box by screws or otherwise, carrying the lugs

p', between which the lug p², which is secured to the under side of a flat spring, Q, fits, and is pivotally secured by means of the removable pin or bolt p³. The spring Q curves 70 in opposite directions, its longest end running down alongside the middle of the concave, and its shortest end standing out beyond the box. To this end a rod, R, is hooked, its lower end being caught within the forks 75 of the spring S, which is fastened to the side of the box and curves outwardly therefrom. This device gives great staying power to the concave, and yet gives when a pressure greater than the resisting power of the springs 80 Q S is exerted on the concave, but still preserving the pressure on the goods under treatment, so as to secure the best results. This pressure is uniform and steady on the goods, and prevents them being cleansed only in 85 streaks.

It is often necessary to adjust the size of the mouth of the concave to receive very large articles; and for this purpose I attach the wire loops w w, one on each side of the 90 mouth, to the concave, and secure a chain, w', thereto, whereby the mouth may be widened and the chain secured to a hook in the side of the box.

The side pieces, T, are held in position by 95 means of the iron brace-bars t, which enter openings in the edges of the pieces T.

The articles to be cleansed are placed between the roller and concave; or they may be laid directly on the roller, which, upon being rotated, carries them forward to and between the concave and itself, turning the goods round and round in an opposite direction to its direction of rotation, and brings them back and over the roller again. 105

Having thus described my invention, what I claim as new, and desire to secure by Letters Patent, is—

1. The combination, in a washing-machine, of the yielding roller or drum H, the yielding concave M, the springs P O', the retaining-irons b, the guides C, and means for holding the springs P in position, substantially as described. 110

2. The combination, in a washing-machine, 115 of the yielding roller or drum H, the yielding concave M, the springs P O', the retaining-irons b, the guides C, rock-shaft D, and rod E, substantially as and for the purpose set forth. 120

3. The combination, in a washing-machine, of the roller H, the yielding concave M, the bow-springs P, curved springs O', retaining-irons b, guides C, the auxiliary hinged spring Q, rod R, and curved spring S, secured to the 125 box A, substantially as described.

4. A concave or bed for washing-machines, consisting of the staves o, spring-metal bands O, having their edges beveled, and the corrugated rubbing-surface n, the ends only of 130 the latter being secured to the staves, substantially as and for the purpose set forth.

5. The combination, in a washing-machine, of the drum or roller H, the elliptical springs F, provided with a bearing for said roller, the springs G, bent lever K, supporting-irons L, having the perforations l, and rod m, whereby the springs F may be adjusted, substantially as described.

In testimony whereof I affix my signature in presence of two witnesses.

PETER BULGER.
